HYDROPNEUMATIC APPARATUS FOR DEVELOPING AND MAINTAINING HYDROSTATIC PRESSURE

George B. Lytle, Cleveland, Ohio; Effie Carr Lytle, executrix of said George B. Lytle, deceased, assignor to W. W. Lytle and C. R. Webber, trading under the name of Lytle Engineering Company, Cleveland, Ohio, a partnership

Application May 16, 1946, Serial No. 676,272

1 Claim. (Cl. 103—48)

1

This invention relates to systems for developing and maintaining hydrostatic pressure, particularly for use in industrial installations in which it is desired to obtain close control of the operation of hydraulic rams and presses, and also to a novel combination of a simplex double-acting hydraulic pump and a double-acting air cylinder constructed and arranged for balanced operation from a common source of pneumatic pressure.

Among the objects of the invention is to provide a hydraulic pressure-developing and utilizing system capable of developing hydraulic power for presses or similar devices and for testing boilers and other vessels on a closed system and which eliminates the necessity of utilizing bypass valves, or other power-consuming pump controls when a predetermined pressure is reached.

Another object of the invention is to provide a hydrostatic pressure-developing system capable of operating at such a rate of speed as to compensate for leaks and maintain a constant predetermined pressure after a desired predetermined pressure is reached.

Another object of the invention is to provide a hydraulic pressure-developing system capable of developing and holding a predetermined hydrostatic pressure and automatically coming into action on but a slight reduction of the pressure developed and desired to be maintained.

Another object of the invention is to provide a novel power and pumping assembly comprising a double-acting pneumatic cylinder for providing power and a simplex double-acting hydraulic pump so arranged in relation to each other as to maintain hydraulic pressure over a long holding period and respond automatically to restore the desired holding pressure immediately upon slight diminution of the desired holding pressure due to the leakage from valves, packings, connections, etc. Other objects involving novel constructions and combinations of parts will appear in the specification in which I have set forth what I now consider the best mode of applying the principles of my invention.

Referring to the drawings,

Fig. 1 is an elevational view of a power and pumping assembly;

Fig. 2 is a schematic diagram of the power and pumping assembly in one form of hydraulic-pressure developing and utilizing system;

Fig. 3 is a schematic diagram of the power and pumping assembly in another form of hydraulic-pressure developing and utilizing system;

Figs. 4 and 5 are sectional views, respectively, 55 bolts 38 and 39. Cross-bar 36 is fastened in fixed

2

of the upper and lower portions of the power and pumping assembly;

Fig. 6 is an elevational view of means for controlling the application of compressed air or other fluid medium alternately to opposite sides of the piston of the power unit; and

Fig. 7 is an elevational view taken from the right side of Fig. 6.

As shown in Figs. 1, 4 and 5, the pump is a simplex double-acting pump comprising a unitary cylinder or cylinder block 10 having secured to its lower end a flanged ring 11 which is fastened to a plate 12 by cap screws. Plate 12 is part of a frame which includes four standards secured at 10 their upper ends to the corners of plate 12 and secured at their lower ends to a base plate 13. Two of the standards 14 and 15 are illustrated in Fig. 1. A third plate 16 is fastened to the standards intermediate the upper and lower plates 12 and 13.

The power unit 17 is secured to plate 16 by means of a number of bolts depending from plate 16 and passing through the upper and lower cylinder heads 18 and 19 of the cylinder 20 of the power unit. Cylinder 20 has a port 21 in the upper cylinder head 18 and a port 22 in the lower cylinder head 19, Fig. 5. The frame by which the pump cylinder 10 and the power cylinder 20 are supported holds these cylinders in spaced relation with the axes of the cylinders in alignment. The power unit is double-acting and has a piston 23 to which a piston rod 24 is attached. The piston rod extends from the upper surface of the piston through a stuffing box 25, as shown in Fig. 5.

35 The unitary pump cylinder 10 is bored from either end to provide upper and lower chambers 26 and 27, respectively, Fig. 4. Chamber 26 is provided with an inlet port 28 and an outlet port 29. Chamber 27 is provided with an inlet port 30 and an outlet port 31. The respective chambers contain plungers 32 and 33 which are tied together for unitary operation so that one plunger enters its chamber as the other plunger is retracted from its chamber. The upper end of chamber 26 is closed by plunger 32 and a guide ring 34 which snugly engages the interior of the chamber and provides a bearing surface for the plunger. The upper end of cylinder block 10 is enlarged and accommodates a bushing 35 by which the plunger 32 is laterally supported. This bushing serves as a bearing for the plunger. Bushing 35 is held in place by a cross-bar 36 which is bolted to a flanged ring 37 by means of

relation to the cylinder block 10 and plunger 32 freely extends through opening 48 in the cross-bar. The upper end of plunger 32 is in threaded engagement with a yoke 42.

The lower plunger 33 is mounted for reciprocation in its chamber 27. Plunger 33 extends downwardly through a guide ring 43, Fig. 5, and a bushing 44 which closes the enlarged opening 45 at the lower end of the cylinder block 10. Bushing 44 is held in place by a cross-bar 46 which is bolted to the flange of ring 11 by means of a pair of bolts 48, 49.

Flange ring 11 is secured to the lower end of cylinder block 10 and to the upper plate 12 of the supporting frame. The lower end of the plunger 33 is threaded at 50 and engaged to a yoke 51. Yokes 42 and 51 are tied together by means of a pair of connecting rods 52, 53, each of which is secured at its ends to the yokes so that the two plungers will work together. The two connecting rods are slidably guided by flanged rings 11 and 37. A threaded rod 54 connects yoke 51 with piston rod 24. This threaded rod is in engagement with a threaded bore 55 in the yoke and a threaded bore 56 in the end of the piston rod. When the position of the piston with respect to the plungers is correctly adjusted the threaded rod 54 is locked in position by nuts 57, 58. 59 is a cam disk whose position on the threaded rod is adjustable to time the operation of the valves which control the supply of fluid pressure to the power unit, as will be explained hereinafter.

As illustrated in Figs. 6 and 7, the flow of compressed air or of other elastic fluid to the upper and lower ends of the power unit is controlled by a pair of valves 60, 61. These valves are operated by cam 59 when it reaches the upper and lower ends of the stroke of the piston. The compressed air is applied from a source (not shown) and the delivery pressure is controlled by a pressure-reducing valve 62. The air pressure is provided through conduit 63 and is effective upon valves 60 and 61 through conduits 64 and 65, respectively. As shown in Fig. 6, cam 59 has reached the upper end of its stroke and the control button 66 is depressed. In this position air travels through conduit 64, control valve 60, conduit 67 and into port 68 of the remote control valve 69. The plunger in this remote control valve is thereby moved to the left. This permits the air to pass from conduit 63 through conduit 70, remote control valve 69, conduit 71, to port 21 at the upper end of power cylinder 20. At the same time port 22 at the lower end of the power cylinder 20 and conduit 72 are opened to the atmosphere by remote control valve 69 to allow the air in the lower part of power cylinder 20 to escape as the piston is forced downwardly.

The air which is entering the top of the power cylinder 20 will drive the piston down until the cam 59 depresses the button 73 of valve 61. When this occurs, the plunger in remote control valve 69 is moved to the right by the air pressure operating through conduit 65, valve 61, conduit 74 and port 75. With the plunger within remote control valve 69 to the right, air flows through conduit 70, remote control valve 69, conduit 72 and port 22 to the under side of piston 23, and as the piston moves upwardly, the air above the piston is exhausted through port 21, conduit 71, and remote control valve 69, to the atmosphere. This cycle of operation is repeated as the piston moves upwardly and downwardly. If the cam 59 should happen to be in an intermediate posi-

tion after operation has been discontinued, the pump can be put into operation by manually pressing one of the buttons 66 and 73 after the air pressure has been turned on. The button valves and the remote control valve are of standard constructions.

The valve system assures constant application of power during the full cycle of the pump. There is no interruption of air supply to one side of piston 23 until after the button at the end of a stroke has been depressed. After the button has been depressed the air from the button valve immediately reverses the position of the plunger in the remote control valve and the air piston is driven in the opposite direction under the same pressure that obtained during the previous stroke. The pneumatic pressure for supplying the power cylinder may be adjusted to a desired operating pressure by the reducing valve in the line supplying the power cylinder. As the piston travels, plungers 32 and 33 of the pump successively operate to compress and reject the hydraulic fluid contained in their chambers 26 and 27 of the pump.

The operation of the power and pumping unit is such as to maintain a desired hydraulic pressure in conduit 78 on the discharge side of the pump, Fig. 2, with which both pump chambers 23 and 27 are connected. Plunger 32 maintains the pressure as it moves downwardly and plunger 33 maintains the pressure as it moves upwardly. Liquid is drawn into the upper chamber 26 through port 28 and conduit 79 during the up-stroke of plunger 32, and liquid is drawn into chamber 27 through port 30 and conduit 80 during the down stroke of plunger 33. The power and pumping unit is immediately responsive to restore and maintain the desired hydraulic pressure on slight diminution of the hydraulic pressure due to the leakage from valves, packings, connections, etc., in the hydraulic system. The sensitivity of response to a drop in hydraulic pressure in the system is accomplished by arranging the power cylinder and the plungers of the pump in vertical alignment with the power cylinder lowermost and the piston of the power cylinder connected to the plungers of the pump. With this arrangement, though the same effective pneumatic force is delivered to the piston during successive strokes, the same pressure is developed in each of the hydraulic chambers of the pump because the effect of the reduced area of the upper surface of the piston is compensated by the weight of the moving parts. The balance thereby obtained imparts a "floating" characteristic to the moving parts whereby stalling due to inertia is avoided and equal sensitivity in both directions of the stroke is effected. The valves for controlling the application of pneumatic pressure to opposite sides of the piston is under the control of the piston and there is no interruption of supply to the cylinder except for subjecting the alternate ends of the piston to pressure for reversing the stroke.

The relationship of the pump and the power cylinder is such that practically any hydraulic pressure can be obtained, depending upon the pneumatic pressure and the ratio of the diameters of the power cylinder and of the hydraulic plungers. If it is desired to develop and maintain a hydrostatic pressure of 2,000 lbs. per square inch, for example, the units are so proportioned as to produce this hydraulic pressure while operating under a given pneumatic pressure and come to rest when the desired hydraulic pressure

is reached. Because of the "floating" characteristics of the moving parts, only a slight drop in the developed hydrostatic pressure, whichever side of the pneumatic piston is at the time subjected to pressure, will cause the pump and the power unit immediately to react and build up the original pressure; which is, in the example noted, 2,000 lbs. per square inch. In other systems, power has necessarily been consumed during a pressure holding period because of such factors as the loss of power involved in converting energy into power for operating auxiliary controls, bypassing through a relief valve, the friction in a relief valve and the need to cool the liquid. As a consequence, the invention effects economies in operation, as well as more dependable holding power for maintaining a predetermined hydraulic pressure requisite for many industrial operations.

The hydraulic system illustrated in Fig. 2 includes a closed reservoir 82 containing compressed air or other elastic fluid medium in its upper portion, and a non-compressible fluid medium in its lower portion. This non-compressible fluid medium may constitute water, oil, or a mixture of soluble oil and water. This non-compressible fluid medium is distributed throughout the conduits, pump and piston-chambers of a press. The lower end of the reservoir is connected by a conduit 83; valve 84 and a conduit 85 to the piston chamber 86 of the press. Conduit 87, connected to conduit 85, is connected to conduit 78 through a valve 88. Conduit 78 is connected through valve 89 with conduit 90 through which fluid pressure may be delivered to the pressure side of pistons 91 and 92 by which movable platen 93 is moved away from fixed platen 94. Conduit 90 has connection with conduit 95, and the liquid contained in reservoir 82 through valve 96. Supply check valves 97 and 98 are interposed between conduit 95 and conduits 79 and 80, respectively, leading to the upper and lower chambers of the pump. Discharge check valves 99 and 100 are interposed between conduit 78 and the upper and lower chambers, respectively, of the pump.

When the press is in open position at the start of a press-operating cycle, the valves are disposed as follows: valve 84 open; valve 88 closed; valve 89 open; valve 96 closed. The pressure developed by the pump is thereby communicated to pistons 91 and 92. To close the press on low pressure, the valves are disposed in the following positions: valve 84 open; valve 88 closed; valve 89 closed; valve 96 open. With this arrangement of the valves, the ram-chamber 86 is actuated and subjected to pressure by fluid flowing from reservoir 82 through conduit 83—85, and the liquid in the retracting cylinders is expelled to conduit 90—95. For some operations it is desirable to momentarily release the pressure for "gassing" purposes, as when molding plastics and rubber, and this may be accomplished at low pressure by leaving valve 84 open and valve 88 closed, closing valve 96 and opening valve 89, thereby subjecting the pistons 91 and 92 to the pressure of the pump. The valve 89 may be momentarily opened and closed for varying the effective pressure on the moving platen 93.

To close the press on high pressure, the valves are disposed as follows: valve 84 closed; valve 88 open; valve 89 closed; valve 96 open. With this arrangement of the valves, full pressure of the pump is delivered through conduit 87 to the ram and the liquid expelled by retracting pistons 91 and 92 is transmitted to conduit 90—95 and the

reservoir. For momentarily "gassing" on high pressure the valves are disposed as follows: valve 84 open; valve 88 closed; valve 89 open; valve 96 closed. The ram is thereby cut off from the pressure developed by the pump and the pump pressure is directed to retracting pistons 91 and 92, valve 96 being closed to prevent the flow of liquid from the retracting cylinders to the reservoir. To again close the press on high pressure, the disposition of the valves for obtaining high pressure as above described may be restored.

The cycle of operation of the press is completed by returning all of the valves to the positions initially described with reference to their disposition at the start of the press-operating cycle. Because of the sensitive responsiveness of the pump to variations in pressure, the hydraulic pressure operable on the pistons of the press is maintained substantially constant.

The hydraulic system illustrated in Fig. 3 includes a reservoir 101 which is partially filled with hydraulic fluid and vented to the atmosphere. The pressure condition for low pressure press operation is established by the head of liquid within the reservoir. The lower end of the reservoir is connected by a conduit 103; valve 104, and conduit 105 to the ram or piston chamber 106 of the press. Conduit 105 is connected through valve 107 with conduit 108 from which a branch connection 109 extends to the pressure sides of the auxiliary lifting pistons 110 and 111. Conduit 108 is connected through valve 112 to conduit 113 having branch connections with discharge check valves 114 and 115, of the pump. Supply check valves 116 and 117 are connected to conduit 118 which is connected to conduit 103, and thereby connected to the bottom of the supply reservoir 101.

When the press is in an open position at the start of a press operating cycle, the valves are disposed as follows: valve 104 open; valve 107 open; valve 112 closed. In this condition the press is open and subjected only to the hydrostatic head of fluid in reservoir 101 on pistons 106, 110 and 111. To close the press the valves are disposed as follows: valve 104 open; valve 107 closed; valve 112 open. With this arrangement the hydraulic pressure developed by the pump is applied to the auxiliary lifting cylinders 110 and 111. The ram chamber 106 is maintained full by the flow of liquid from reservoir 101. For momentarily relieving the pressure on the press, as when it is desired to gas a mold, the valves are disposed as follows: valve 104 open; valve 107 open; valve 112 closed. In this arrangement the hydraulic pressure developed by the pump is shut off but pressure is maintained on the press by the hydrostatic head of fluid in reservoir 101 acting upon the auxiliary lifting pistons 110 and 111 and the ram 119. To close the press on high pressure the valves are disposed as follows: valve 104 closed; valve 107 open; valve 112 open. The full hydraulic pressure developed by the pump is then applied to the auxiliary lifting pistons and to the main ram. At the completion of the pressing operation the press is opened by restoring all the valves to their initial positions as described for the start of the cycle.

In both systems illustrated in Figs. 2 and 3, all of the valves may be closed at the same time for safety purposes, and also for setting up dies, as in molding plastics and rubber. By closing all of the valves at one time the oper-

ator can stop the travel of the movable platen in any position.

What is claimed is:

In a pressure supply apparatus for supplying liquid under pressure to an hydraulic system in order to develop a definite pressure, a double-acting pump having aligned bores with inlet and outlet ports and a pair of oppositely acting plungers of substantially equal diameters connected together for successively pumping liquid under the same pressure from their respective bores upon reciprocation of the plungers, a power supply system including a double-acting pneumatic cylinder motor having connections with piping and a pressure reducing valve for controlling the pressure of air from the piping to said pneumatic cylinder motor, means controlled by said plungers and including valves for automatically making effective the controlled air pressure upon opposite sides of the piston of the pneumatic motor always to apply constant pressure to one side or the other of the piston to move or to hold the piston, depending upon any change or lack of change in the hydraulic pressure desired to be developed in the bores of the double-acting pump, the plungers of said pneumatic cylinder motor being connected in line with the piston of the pneumatic motor and disposed vertically with the pneumatic motor located below the hydraulic pump and the combined weight of the plungers and piston and their connected moving parts be-

ing effective against the pneumatic pressure required to hold or move the piston upwardly and supplementary to the pneumatic pressure effective to hold or move the piston downwardly so that the piston and connected plungers are substantially equally responsive to a constant pneumatic pressure exerted on either the upper or lower surface of the pneumatic piston and the hydraulic pressure developed by the plungers of the associated pump is maintainable substantially constant over a relatively long period.
